John E. Earle

United States Patent Office.

EARLE A. SMITH, OF WATERBURY, CONNECTICUT.

Letters Patent No. 96,981, dated November 16, 1869.

IMPROVEMENT IN BUCKLES FOR CLOTHING.

The Schedule referred to in these Letters Patent and making part of the same.

To all whom it may concern:

Be it known that I, EARLE A. SMITH, of Waterbury, in the county of New Haven, and State of Connecticut, have invented a new Improvement in Buckles; and I do hereby declare the following, when taken in connection with the accompanying drawings, and the letters of reference marked thereon, to be a full, clear, and exact description of the same, and which said drawings constitute part of this specification, and represent, in—

Figure 1, the frame,

Figure 2, the tongues,

Figure 3, a transverse section of the buckle, and in

Figure 4, a top view of the buckle complete.

This invention relates to an improvement in buckles for wearing-apparel; and consists in the formation of the frame, loop, and means of connection for the tongue from a single piece of metal, and the tongues of a second piece.

To enable others skilled in the art to fully understand my invention, I will proceed to describe the same, as illustrated in the accompanying drawings.

From sheet-metal, or other suitable material, I cut the frame, as seen in fig. 1, so as to form a loop, A, the bar B of which serves as a means for the fixed attachment of the buckle, the bar C, for the tongues to rest upon.

Upon each of the ends D, I leave portions, E, of

the same metal as a means of securing the tongue, as hereafter shown; also the bar F extending from end to end forward of the bar B, all as seen in fig. 1.

Then, from another piece of metal, I form a bar, G, with tongues H H, more or less in number, preferring to make this of sheet-metal, the two ends f of the bar G being bent or worked into the form, as seen in fig. 3, to form a suitable hinge.

The parts E of the frame are struck below the frame, as seen in fig. 3, and the tongue laid beneath them, and the parts E bent around the ends f of the tongue-bar, so as to form the hinge, as seen in figs. 3 and 4, and the buckle is complete.

It will be observed that by this construction is formed the bar B for the means of attachment, and the tuck-loop is formed by the interposition of the bar F between the bar B and the tongue-bar G.

Having fully described my invention,

What I claim as new and useful, and desire to secure by Letters Patent, is—

The herein-described buckle for clothing, consisting of the frame B C D, with the tuck-bar F, and hinge-bar G, secured to the frame, substantially as set forth.

EARLE A. SMITH.
